UNITED STATES PATENT OFFICE

EWALD F. TECHMER, OF CHICAGO, ILLINOIS, ASSIGNOR, BY MESNE ASSIGNMENTS, TO
NATIONAL KELLASTONE COMPANY, OF CHICAGO, ILLINOIS, A CORPORATION OF
DELAWARE

WALL CONSTRUCTION

Application filed October 6, 1928. Serial No. 310,751.

The present invention relates to wall construction, and is particularly concerned with wall construction for partitions and the like. The present application is particularly concerned with a modified form of a base block shown in my Patent No. 1,681,311, issued August 21, 1928.

One of the objects of the invention is the provision of a novel wall construction, including a base block having grounds for plastering formed thereon; said block being formed with shoulders for aligning a wall core and having a bottom similarly formed so as to make the block reversible and to simplify the installation.

Another object is the provision of a base block constructed of any magnesite composition which is readily severable and which includes grounds for plastering and longitudinal recesses closed by baseboards for enclosing wiring conduits and the like.

Another object is the provision of a novel base block form which is reversible, and which includes grounds for plastering, recesses for conduits, and shoulders for aligning a wall core on the block.

Other objects and advantages of the invention will be apparent from the following description and from the accompanying drawing in which similar characters of reference indicate similar parts throughout the several views.

Referring to the drawing, of which there is one sheet;

Fig. 1 is a view in perspective of a portion of a wall constructed according to the present invention;

Fig. 2 is a sectional view of the base block and wall of Fig. 1;

Fig. 3 is a view in perspective of the base block alone;

Fig. 4 is a sectional view of a modified form of base block.

The base block of the present invention may be constructed of any magnesite compo-

sition, such as for example, the compositions of matter described in my co-pending application, Serial No. 295,593, filed July 26th, 1928 on wall construction. Such compositions of matter are readily severable by ordinary tools, thereby permitting the base blocks to be sawed off to fit them in place between doors, windows or other walls, and about pipes or conduits in walls. This composition of matter also possesses the property of receiving nails and permitting other parts to be fastened thereto by means of nails or screws without splitting the block.

Referring to the drawing, 10 indicates in its entirety a wall construction made according to the present invention, including a plurality of base blocks 11, a wall core 12, base boards 13 and 14, and plaster coats 15 and 16.

The base blocks 11 comprise molded magnesite members, the mold of which is provided with a core to form a recess 17 for the purpose of saving material and providing a dead air space in the block.

The base blocks 11 are preferably provided with the relatively flat upper and lower surfaces 18, either of which may be used for supporting the wall core 12, the width of either surface 18 being substantially equal to the thickness of the brick, tile or other material of which the partition is to be constructed.

On each side of the surface 18 the block is provided with a shoulder 19, which may slope slightly outward if desired, and which is adapted to align the wall core 12 with the blocks 11. Adjacent the shoulders 19 on each side the block is provided with the plaster engaging surfaces 20, which are of a width substantially equal to the plaster coat or coats, which are to be applied to the wall, and the outer flat surfaces 21 and 22 of the block may thus be employed for grounds in plastering.

It should be noted that the shoulders 19 automatically align the wall core relative to

the plaster grounds 21 and 22, and it is absolutely unnecessary to use any furring strips for forming plaster grounds, thereby eliminating a great deal of labor in the building 5 of the wall. The shoulders 19 also provide a relatively strong construction between the base block and wall core, since the shoulders positively prevent the wall core from getting out of place relative to the block.

10 In order to make the block reversible so as to simplify its installation, the bottom 18 of the block may be provided with similar shoulders 19, similar surfaces 20 and similar plaster grounds 21 and 22, and the plaster coat 15 engaging surfaces 20 may form the surfaces upon which the block rests when used in a wall. In the construction of the wall, it is thus immaterial which side the artisan may 20 grasp and much time is saved in the installation of the base blocks since it is unnecessary to turn them over or to lay in any particular way and either of two sides may serve as the bottom or top.

15 The base blocks 11 are preferably provided with longitudinally extending recesses 23 on one or both sides, and these recesses may be curved as in Fig. 4, or formed by three or more flat surfaces 24, 25 and 26 as in Fig. 3. In either case, sufficient material should be 30 left on the side of the block adjacent the top and bottom to form the plaster grounds 22, and to form a surface against which a baseboard 13 or 14 may be secured.

25 Fig. 4 is a modified form of base block 11 of substantially the same shape as that shown in Fig. 2, but having curved lateral recesses 23 for receiving wiring conduits or the like.

Referring to Fig. 2, it will thus be noted that after the wall has been constructed, and 40 the plaster coats 15 and 16 applied, the baseboards 13 and 14 of wood, marble or any convenient material, may be used to close the recesses 23. The recesses 23 may be used for installing wiring conduits 27 for electric light 45 wires, gas pipes, water pipes, or loose wires, such as are used in annunciator systems.

When the wiring or piping has been installed the baseboards 13 and 14 may be secured by a plurality of screws 28 passing 50 through the baseboards and screwed into the base block, and as the base block is constructed of a material which will readily receive screws, the baseboards are thereby firmly secured and they may be readily removed at any time to inspect the wiring or to install further wiring or pipes.

The wall construction may also be provided with quarter-round molding 28', and with any other appropriate molding 29 above 60 the baseboard, the latter being also secured by diagonally driven screws 30, screwed into the base blocks 11 at points between the screws 28.

It will thus be observed that I have invented a novel form of base block, which is

provided with plaster grounds for automatically locating the plaster surface, and with longitudinal side recesses closed by the baseboards for receiving piping or wiring.

70 My base block is more easily manufactured and more cheaply installed than any of the base blocks of the prior art, and it provides a finished wall construction, in which the piping, wiring or other installation is always accessible.

75 The magnesite block is also readily worked into any size for fitting between doors or partitions, and it is also adapted to receive nails or screws for fastening the block in place, or securing other parts to the block.

80 While I have illustrated a preferred embodiment of my invention, many modifications may be made without departing from the spirit of the invention, and I do not wish to be limited to the precise details of construction set forth, but desire to avail myself of all changes within the scope of the appended claims.

85 Having thus described my invention, what I claim is new and desire to secure by Letters Patent of the United States, is:

90 1. In a wall construction, the combination of a base block of magnesite composition with a wall core, said block having a longitudinally extending recess in its side for wiring and the like, and a baseboard for closing said recess.

95 2. In a wall construction, the combination of a base block of magnesite composition with a wall core, said block having a longitudinally extending recess in its side for wiring and the like, a baseboard for closing said recess, said block having a wall core supporting surface, plaster coat engaging surfaces and plaster grounds formed thereon.

100 3. A base block for interior partitions comprising a member of magnesite composition, having a body formed with a depression in its top and bottom for aligning a wall core, and a longitudinal depression formed in its side for receiving conduits, said longitudinal depression being closed by a base board.

105 4. A base block comprising a magnesite body having a flat top and bottom, shoulders carried at each side of said top and bottom for aligning a wall core, plaster coat engaging surfaces adjacent said shoulders, and plaster grounds adjacent said plaster coat engaging surfaces.

110 5. A base block comprising a magnesite body having a flat top and bottom, shoulders carried at each side of said top and bottom for aligning a wall core, plaster coat engaging surfaces adjacent said shoulders, plaster grounds adjacent said plaster coat engaging surfaces, and having conduit recesses formed in its sides.

115 6. A unitary building block comprising a block of nailable material having a longitudinally extending groove along one side for

housing conduits and the like, said block having a flat top to receive wall members and having a narrow flat ledge at the edge in a horizontal plane different from the plane of the top of the block, for the purpose described.

7. A unitary partition block comprising a block of nailable material having a longitudinally extending groove at each side thereof to form housings for conduits and the like, said block having a flat top and narrow ledges at each side of the top in horizontal planes offset from the plane of the top of the block, for the purpose described.

15 In witness whereof, I hereunto subscribe my name this 4th day of October, 1928.

EWALD F. TECHMER.
